UNITED STATES PATENT OFFICE.

ALBERT HUGUENIN, OF ZÜRICH, SWITZERLAND

ROTARY COMPRESSOR.

1,036,627.

Specification of Letters Patent. Patented Aug. 27, 1912.

Application filed August 16, 1909. Serial No. 513,109.

To all whom it may concern:

Be it known that I, ALBERT HUGUENIN, a citizen of the Republic of Switzerland, residing at Universitätsstrasse 33, Zürich, Switzerland, have invented certain new and useful Improvements in or Relating to Rotary Compressors; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to impellers for high speed rotary compressors. Cast wheels, even if made of brass or steel are too heavy. Riveted wheels have been proposed, but it has been found that the strains on them are very heavy, as their resistance to vibration and oscillation is not sufficient.

This invention remedies the above-mentioned serious drawbacks.

It consists in making an impeller having sheet metal vanes fixed to a hub at their inner ends, this being the only point where they are held, while for the remaining and greater part of their length they are free.

The vanes are of U or Z shape. Their width and thickness decreases toward their outer ends so that they are practically bodies of equal strength. Owing to this construction only the vanes produce any considerable centrifugal action, while the hub has a small circumferential velocity, and consequently the centrifugal forces produced are not considerable, so that it may be made strong enough to bear the centrifugal action of the vanes.

The vanes themselves are stiffened by their U- or Z-shape in such manner that no loosening takes place, and they are therefore specially adapted for working at very high circumferential speeds without any inconvenience, with the greatest safety and for long periods. As the compression capacity of a rotary wheel increases with the square of the circumferential speed, such rotating wheels can pro-

duce high pressure per stage. For a given total increase of pressure only a few are required. The wheels themselves have the smallest possible weight, and as only a few of such light wheels have to be mounted on one spindle for producing even a great increase of pressure, the spindle can be made with

a comparatively small diameter. This again enables stuffing boxes and bearings with small bores to be used, which results in small loss by leakage or friction. A machine provided with such rotating wheels is therefore light in weight, has a small length and works in a highly economical manner.

The accompanying drawings show by way of example constructions according to this invention.

Figure 1 is a cross section, and Fig. 2 is an elevation of an impeller the vanes of which are on one side of the hub only. Fig. 3 is a section of an impeller having vanes on both sides of the hub. Figs. 4, 4^a and 4^b are side views of the vanes assembled and in different positions. Fig. 5 is a section of an impeller having vanes on one side only and designed for high velocities. Figs. 6 and 7 are perspective views of different forms of vanes.

The vanes *a* each consists of a web portion 2 and lateral flanges 3, said flanges being either directed toward the same side of the web to form a vane U-shaped in section, or directed toward opposite sides of the web 2 to form a vane Z-shaped in section, as shown in Figs. 6 and 7. The flanges of the U-shaped vanes, Fig. 2, are continued forward at their bases, as indicated at 4, in the direction of rotation of the wheel, and to such an extent that they overlap the flanges of the preceding vanes and are riveted to the latter. In this way a very light and very efficient stiffening of the vanes with respect to each other is obtained at and adjacent to the elements to which they are secured, be it a hub, as *b* or a ring, as *c*.

Fig. 3 shows in cross section an impeller having inlets on both sides. The vanes *a* thereof are arranged in pairs, with their adjacent flanges against each other, the vanes being U-shaped in section. The adjacent flanges of each pair of vanes are held by a stiffened hub *b* and their outer flanges 3 are stiffened by rings *c*. Each ring *c* has a channel on its outer periphery in which is wound a wire winding *d* that neutralizes or takes up the centrifugal forces of the stiffening rings *c* and the centrifugal forces of those portions of the vanes that transmit said forces to said rings. This winding *d* is preferably put on with an initial tension calculated to counteract the centrifugal forces on the ring so that the outer flanges

3 of the vanes will not expand or be subjected to greater or less strains than the inner flanges when the impeller is working at full speed. The object of this is to avoid 5 injurious bending strains on the vanes, one-sided bending of the same, and an untrue rotation of the impeller. This point is to be more particularly considered with relation to impellers that have an inlet at one 10 side only.

In Fig. 4^a the vanes *e* are so assembled that their webs are not radial, but are inclined slightly forward in order that the 15 lines through the resultant centers of gravity of the webs and flanges taken together and the axis of the impeller will be radial, in order to subject the vanes to tension only 20 and not to bending. The vanes *f* Fig. 4^b are shown as inclined backward for the purpose 25 of guiding the air more efficiently.

The wire winding *d* may be replaced by 30 rings *g* Fig. 5. These stiffening rings may be of drawn or wrought metal, and are either driven or shrunk into place. One 35 ring *g* is secured on the hub portion *b* and is held in the state of rest of the impeller with an initial tension which produces a compression on the hub *b* and on the blades *a* toward the axis of rotation of the impeller 40 which exceeds the centrifugal force tending to expand it when the impeller is rotating at full speed. The compression is partly decreased when the impeller assumes its full speed and the centrifugal action comes into 45 operation. This tension does not relate to the ring *c* but to the ring *g*.

The flanges 3 of the U-shaped and Z-shaped vanes may be diminished in width 50 toward the periphery of the wheel, or may 40 be dispensed with altogether at or near the periphery, or the U-shape may merge into crescent shape at the periphery. The main point is that the shape deviating from a plane must, to a considerable extent, be beyond the securing rings, and thus the overhanging vanes considerably stiffened.

The invention consists essentially of an 55 impeller having sheet metal vanes for high speed rotary compressors in which that part of the vanes which projects beyond the hub is U-shaped or Z-shaped in section; a modification in which the vanes are secured to a stiffening ring and to the hub Fig. 5; a modification in which the vanes are secured 60 to the hub and are also secured to each other Fig. 2; a modification in which the inner flanges of the vanes lie in the plane of the 65 wheel and are secured to the hub and the

outer flanges are secured to the stiffening rings Fig. 3. The stiffening ring or the hub 60 can be stiffened by shrunk rings or wire or band windings.

I claim—

1. An impeller for rotary compressors, comprising a hub, sheet iron vanes secured 65 thereto, the vanes extending freely beyond the outer circumference of the hub and having lateral strengthening flanges, the sectional area of the vanes decreasing gradually toward their outer ends, each vane being 70 fixed to the hub with one lateral flange and a supporting ring fixed to the other lateral flange, said supporting ring having no immediate connection with the compressor shaft.

2. An impeller for rotary compressors, comprising a hub, sheet iron vanes secured thereto, the vanes extending freely beyond the outer circumference of the hub and having lateral strengthening flanges, the cross- 80 section of each vane being broken-line shaped, the sectional area of the vanes decreasing gradually toward their outer ends, each vane being fixed to the hub with one lateral flange and a supporting ring fixed 85 to the other lateral flange, said supporting ring having no immediate connection with the compressor shaft.

3. An impeller for rotary compressors, comprising a hub, sheet iron vanes secured 90 thereto, the vanes extending freely beyond the outer circumference of the hub and having a lateral strengthening flange on each edge of the guiding-face of each vane, the cross-section of each vane being broken-line 95 shaped, the sectional area between the flanges and the guiding-face of each vane decreasing gradually toward its outer end.

4. An impeller for rotary compressors, comprising a hub, sheet iron vanes secured 100 thereto, the vanes extending freely beyond the outer circumference of the hub and having a lateral strengthening flange on each edge and on the same side of the guiding- 105 face of each vane, the cross-section of each vane being broken-line shaped, the sectional area between the flanges and the guiding face of each vane decreasing gradually toward its outer end.

In testimony that I claim the foregoing 110 as my invention, I have signed my name in presence of two subscribing witnesses.

ALBERT HUGUENIN.
